Primary Examiner — Sanjeev Paul

(57) **CLAIM**

The ornamental design of an aquatic protective eyewear, as shown and described.

DESCRIPTION

FIG. 1 is a perspective view showing my new design;
FIG. 2 is a front elevational view thereof;
FIG. 3 is a bottom elevational view thereof;
FIG. 4 is a top elevational view thereof; and,
FIG. 5 is a right side elevational view thereof, the left side
being a mirror image.

The portion of the design shown in broken lines is for
illustrative purposes only and forms no part of the claimed
design.

1 Claim, 3 Drawing Sheets
